Des. 235,327

Patented June 10, 1975

235,327

PICK-UP TRUCK CANOPY

Arthur L. Morris, 3406 Austin Court,
Orange, Calif. 92669

Filed Apr. 1, 1974, Ser. No. 456,764

Term of patent 14 years

Int. Cl. D12—16

U.S. Cl. D12—156

Fig. 1

Fig. 2

Fig. 3

FIG. 1 is a front perspective view of a pick-up truck canopy embodying my new design;

FIG. 2 is a side elevational view of the pick-up truck canopy of FIG. 1, the opposite side being a mirror image of the side illustrated; and

FIG. 3 is a rear perspective view thereof.

I claim:

The ornamental design for a pick-up truck canopy, substantially as shown and described.
